TRANSFER FORK

Paul O. Unger, Elmhurst, Ill., assignor to Wilson-Jones Company, Chicago, Ill., a corporation of Massachusetts

Application January 22, 1936, Serial No. 60,154

5 Claims. (Cl. 129—1)

This invention relates to a transfer fork particularly designed for use in transferring a plurality of sheets to or from a loose leaf binder without disarranging the sheets.

5 It is an object of my invention to provide a transfer fork adapted to remove a substantial portion of the sheet contents of a loose leaf binder, retain the sheets securely so that they may be used while on the fork, and to replace them in 10 the binder, or insert them in a different binder, without disturbing the arrangement of any of the sheets. It is a further object of my invention to provide a transfer fork provided with sheet retaining prongs that may be inserted into apertures of sheets contained in a binder when the 15 prongs of the binder are in overlapped position. Other objects of my invention will become apparent upon reading the following description, taken in conjunction with the accompanying drawings, 20 in which:

Figure 1 is a perspective view of a loose leaf binder in half opened position with the transfer fork shown in position for insertion into the sheets to be transferred;

25 Figure 2 is an end elevation of the binder with the transfer fork inserted in the sheets to be transferred;

Figure 3 is a view similar to Figure 2 showing the sheets to be transferred moved into position 30 for removal;

Figure 4 is a view similar to Figure 2 with the binder fully opened and the sheets removed;

Figure 5 is a perspective view of the transfer fork with sheets secured thereto; and

35 Figure 6 is a perspective view of the transfer fork.

The loose leaf binder illustrated is fully disclosed in the application of George H. Dawson, Serial No. 759,611, filed December 29, 1934, which 40 issued as Letters Patent No. 2,073,049, on March 9, 1937. In view of the fact that the specific binder is not part of the invention, it will not be described in detail. The binder comprises a pair of back sections 2 hinged along their meeting 45 edges as indicated at 3. A pair of covers 4 is hinged to opposite edges of the back sections 2, as indicated at 5. A plurality of curved latches 6 are secured to one back section to hold the back sections in closed or in half opened position. The 50 reference numeral 7 designates a finger piece which operates a locking bar (not shown) to release the latches 6 to permit movement of the back sections to opened position. Each back section carries a plurality of arched sheet retaining 55 prongs 8 that overlap each other when the binder

is in half opened position. A plurality of banks of sheets arranged in overlapping relationship is impaled on the sheet retaining prongs 8.

The transfer fork comprises a flat bar 9 having a plurality of sheet retaining prongs 10 secured thereto so as to project beyond one edge thereof. The prongs 10 are curved towards the edge of the bar opposite the edge from which they project and then in the reverse direction. The curvature of the prongs 10 conforms to the curvature of the 10 prongs 8 so that the prongs 10 may be inserted in the sheets impaled on the prongs 8 and will lie flat against said sheets. An elastic cord 11 has one end secured to the bar 9 in any suitable manner, and has an enlarged knob 12 at its free end. 15 The bar 9 is provided with a notch 13 near the end opposite that to which the cord 11 is secured. The bar is also provided with an aperture 14 adjacent each end so that the transfer fork may be hung on a nail.

20 The operation of my improved transfer fork is quite simple. When it is desired to remove a plurality of sheets from a binder, the back sections of the binder are moved to half opened position, and the prongs of the transfer fork are inserted 25 into apertures 15 provided adjacent the binding edge of the sheets, as indicated in Figures 1 and 2. The manner of securement of the prongs 10 to the bar 9 and the direction of curvature of the prongs 10 cause the bar to lie clear of the prongs 8 on the 30 side away from the back of the binder so that the transfer fork prongs can be inserted into the apertures while the sheets are still securely held by the prongs of the binder.

35 The transfer fork and the desired sheets are then moved onto the prongs 8 on the other side of the binder, as shown in Figure 3, and the elastic cord 11 is looped over the sheets and the free end of the cord is then inserted into the notch 13 to hold the sheets on the transfer fork. The back 40 sections are then moved to fully opened position and the transfer fork and sheets secured thereto are then removed, as indicated in Figure 4. The transfer fork and sheets may then be handled as much as desired without disturbing the relative 45 arrangement of the sheets secured to the transfer fork or those left in the binder. The removed sheets may be inserted in another binder or may be replaced in the same binder by merely reversing the steps described above.

50 Although I have described a preferred embodiment of my invention in detail, it will be understood that the description thereof is illustrative rather than restrictive, as many details may be modified or changed without departing from the 55

spirit or scope of my invention. Accordingly, I do not desire to be restricted to the exact construction described, except as limited by the appended claims.

5 I claim:

1. A transfer fork comprising a bar, a plurality of prongs secured to said bar so as to project beyond one edge thereof, an elastic cord secured to said bar, and a notch in said bar adapted to 10 facilitate securement of the free end of said elastic cord.
2. A transfer fork comprising a bar having a plurality of curved prongs secured adjacent one edge of said bar, and elastic means adapted to 15 retain sheets impaled on said curved prongs.
3. A transfer fork comprising a bar and a plurality of prongs secured adjacent one edge of said bar and projecting beyond said edge, said prongs being curved toward the opposite edge of said bar 20 and then in the reverse direction.
4. In combination with a loose leaf binder adapted to be maintained in a half opened position with a plurality of curved sheet retaining prongs in overlapping position, a transfer fork 25 comprising a bar provided with a plurality of

prongs of substantially the same curvature as said first mentioned prongs, said second mentioned prongs being secured to said bar in offset relationship thereto, whereby said second mentioned prongs can be inserted into the apertures of the 5 sheets contained within said binder when said binder is in its half opened position.

5. In combination, a loose leaf binder comprising a pair of back sections having a plurality of curved prongs adapted to overlap to retain a plurality of apertured sheets in said binder, and a transfer fork comprising a bar, a plurality of prongs having a curvature substantially similar to the curvature of said first mentioned prongs secured to said bar in offset relationship thereto, 10 whereby said second mentioned prongs are insertable in said apertured sheets when said first mentioned prongs are in overlapped position, an elastic retaining member having one end secured 15 to said bar, and a notch in said bar adapted to secure the free end of the elastic retaining member to retain a plurality of said sheets on said transfer fork. 20

PAUL O. UNGER. 25
